(57) **CLAIM**

The ornamental design for a game board apparatus, as shown and described.

DESCRIPTION

FIG. 1 is a front perspective view of a game board apparatus showing the new design.

FIG. 2 is a first side view thereof.

FIG. 3 is a second side view thereof.

FIG. 4 is a top view thereof; and,

FIG. 5 is a bottom view thereof.

The broken line showing of bottom of the circular recesses and the central depression is included for the purpose of illustrating portions of the "article" and forms no part of the claimed design.
